UNITED STATES PATENT OFFICE

ROMEO GUILLEMETTE, OF TAUNTON, MASSACHUSETTS

AEROPLANE-STEERING APPARATUS

Application filed December 30, 1929. Serial No. 417,505.

This invention relates to aeroplane steering apparatus, and an object of the invention is to provide a selective or simultaneous control for the rudder, the elevators, and the ailerons that is within the reach of the pilot and that can be operated from the same steer post.

Further objects of the invention are to provide, in a manner as hereinafter set forth, a steering apparatus of the character referred to, which is strong, compact, durable, very light in construction, very simple in its method of assembly, adaptable for installation in all standard types of aeroplanes, and comparatively inexpensive to manufacture and install.

With the foregoing and other objects in view, the invention consists of a novel construction, combination and arrangement of parts, as will be hereinafter more specifically described and illustrated in the accompanying drawings, wherein is disclosed a preferred embodiment of the invention, but it is to be understood that changes, variations and modifications, may be resorted to without departing from the spirit of the claims here-to appended.

In the drawings wherein like reference characters denote corresponding parts throughout the several views:—

Figure 1 is a fragmentary perspective view of an aeroplane illustrating in dotted lines the adaptation of the present invention therewith,

Fig. 2 is a side elevation, partly in section of the steering apparatus,

Fig. 3 is a rear elevation thereof,

Fig. 4 is a vertical section taken substantially on the line 4—4 of Fig. 2 and looking forwardly,

Fig. 5 is a perspective view of the frame and steering post with the elongated sleeve removed therefrom,

Fig. 6 is the elongated sleeve in disassembled relation,

Fig. 7 is a perspective view of the longitudinal shaft,

Fig. 8 is a perspective view of one of the spindle sleeves and coupling forks.

Referring to the drawings in detail, 10

indicates generally an aeroplane and in the form shown, is of the monoplane type. The fuselage of the aeroplane is indicated at 11 and a pair of wings 12, 13 project laterally from the opposite sides of the fuselage 11, 55 and are secured thereto in any suitable manner.

Adjacent the outer corner of each wing there are rockably mounted a pair of ailerons 14 that are supported in pockets 15 on the trailing edge of each wing. Control wires 16 project from and are secured to the opposite faces of the ailerons 14, intermediate the ends of the ailerons and at the leading edges thereof. 65

One of the ailerons is clearly illustrated in Fig. 1 of the drawings, a control wire 17 on the top surface of the wings 12, 13 connect the upper horns 16 of each aileron together, as will be clearly understood by referring to 70 Fig. 1 of the drawings. From each of the lower horns 16, there extends a control wire 18, 19 that are trained over sheaves 20 and the inner ends thereof extend through the fuselage of the aeroplane and are then 75 trained through a pair of sheave wheels 21, 22 supported on the frame of the fuselage and terminate in a coupling fork 23, 24.

The coupling forks 23, 24 are pivoted on the bolts 25, 26 on the free ends of the cross 80 bars 27. As shown, a pair of angular shaped fins 28, 29 are secured to the rear end of the fuselage and project laterally in a horizontal plane therefrom. A pair of elevator planes 30, 31 are rockably mounted at their leading 85 edges to the trailing edges of the fins.

Horns 32, 33 are secured to and project from the opposite faces of the elevators to which are attached the control wires. As 90 shown, the invention is described in connection with a pair of elevators 30, 31 but it is within the contemplation to use a single plane elevator across the rear end of the fin and in this event, there will be used only one horn 95 similar to that shown at either 32, or 33.

In the event there is only one elevator plane used, the rudder to be presently described, will be journaled above the elevator so as not to interfere with its operation. As shown in the drawings, a control wire 34, 35 leads from 100

the lower end of the lower horn 32, 33 and from the ends of the upper horns 32, 33, there extend the control wires 36, 37, all of which extend thru suitable openings in the fuselage and project forwardly to the control mechanism to be described later.

A rudder 38 is journaled to the rear edge of a vertical fin 39 and has horizontal horns 40 projecting from the opposite faces thereof, 10 and the control wires 41, 42 are secured to the ends of the horn and extend thru the fuselage and are connected to the control means as will be presently described.

A longitudinal shaft 43 is journaled in a bearing sleeve 44, that is supported on the upper end of a supporting bracket 45, the lower ends of which are secured to the longitudinal ribs 46 of the fuselage. The shaft 43 is supported additionally by a second bearing 20 sleeve 47 that is supported on a bracket 48 that is also secured to the longitudinal fuselage ribs 46 which are broken in Fig. 2 of the drawings.

To the free outer end of the shaft 43, a cross bar 27 is secured intermediate its ends as shown in Fig. 7 of the drawings. Adjacent the bearing 47, there is a sleeve 49 circumposed about the shaft and is rigidly secured thereto by a set screw 50. Radiating from the inner end of the sleeve 49 are radially disposed stop arms disposed at quadrant about the axis of the sleeve. The two vertically projecting legs 51 are relatively flattened at the free ends as at 52 to form abutments or stops.

35 The oppositely projecting horizontal legs 53 have on their outer ends elongated abutments 54, the sleeve 49 being formed with a circular extension 55 rearwardly of the four radiating legs which is adapted to telescopically fit in the sleeve 56. The sleeve 56 is formed of two semi-tubular shanks 57, 58 each of which merge into laterally disposed prongs 59, 60 formed with openings 61 adjacent the free end of the prongs.

45 The semi-tubular shanks 57, 58 are each provided with a pair of registering openings 62, 63 that register with openings in the extension 55, by which the shanks are secured to the extensions 55 with the prongs 59, 60 50 projecting rearwardly therefrom.

In the assembled relation as indicated generally at 56, the shanks 57, 58, and the prongs 59, 60 form a forked sleeve by which the elongated sleeve 64 is rockably connected to the rear end of the shaft 43. The sleeve 64 is provided with oppositely disposed pivot bolts 65, threaded on their outer ends to receive nuts, and these pivot bolts, are journaled in the openings 61 in the prongs whereby the 60 sleeve 64 is pivoted to the rotatable shaft 43 to form a universal joint.

There is a square frame indicated generally at 66 rotatably supported on the lower end of the steering post 71 having one pair of 65 opposed corners disposed vertically and the

other pair of opposed corners, disposed horizontally. The vertical corners are formed with aligned collars 67, 68 while the horizontal corners are formed with laterally projecting spindles 69, 70. The lower portion of 70 the steering post 71 extends, through and is rigidly secured to the vertical collars 67, 68 by set screws 73. Spaced above the collar 67, there is an annular shoulder 74 formed on the steering post and on the free lower end thereof, spaced below the lower collar 68, there is formed another shoulder 75. Between these shoulders 74, and 75, and the respective collars 67 and 68 there are two sleeves indicated generally at 94, loosely circumposed about 80 the steering post 71.

There are another pair of sleeves indicated generally at 94, loosely mounted on the projecting spindles 69 and 70, and these sleeves, are prevented from slipping from 85 the spindles by a pair of rings 87 that are coupled to the ends of the spindles by pins 88 that are anchored in registering openings in the end of the spindles and rings.

Rotatably mounted on the lower portion 90 of the steering post 71, interiorly of the frame, and between the collars 67, 68 is the elongated sleeve 64 that is pivotally connected as heretofore described to the inner end of the shaft 43. Since the shaft 43 is rotatable and the sleeve 64 is pivoted to the end of the shaft, and the steering post 71 is rotatable in the sleeve, then the steering post is 95 universally connected with the frame 66.

At the upper end, the steering post merges in spaced handles 78, 79 which are gripped by the pilot for operating the controls as will be described later. Each of the collars, indicated generally at 94 are formed in the same manner, and a description of one will 105 suffice, for a clear understanding of the others.

The sleeves are formed with a sleeve body portion 78 from the opposite, outer peripheral face of which there extends a pair of pins 110 79, 80. Adjacent the end, each pin is formed with an opening through which cotter pins 81 extend for holding the forked coupling to be presently described, to the sleeve.

There are four forked coupling members, 115 indicated generally at 82, rockable one on each of the four sleeves 94. The forked couplings are each formed in the same manner, and the following description applied to one of them, will give a clear understanding of 120 the others.

The forked couplings are each formed with a shank 83 apertured on its outer end, the inner end of which merges with laterally disposed arms 84, 85 that straddle the sleeves 94. The free ends of the prongs are provided with openings 86, through which the sleeve pins 79, 80 extend. Cotter pins 81 extend through the free ends of the pins and prevent the fork from slipping off the pins, after the 130

forked coupling is secured to the sleeve body 78.

The forward and rearward rocking of the frame 66 is limited by the vertical stop members 51, while the horizontal stop members 54 form limit stops, when the steering post 71 is rotated on its axis. An upstanding arm 90 is secured at its lower end to a cross rib 91 of the fuselage frame, and is formed adjacent its upper end with laterally extending stop legs 92, 93 to limit the rotation of the cross arms 27 that controls the ailerons so that excess movement will not strain the pivots on the ailerons.

15. The stop members 51 and 54 prevent the straining of the pivot for the elevators 30-31, and the rudders also. Control wires 34 and 35 leading from the bottom horns of the elevators, 30, 31, are secured to the apertured shanks 83 of the forked couplings 82, at the upper corner of the frame 66. The upper control wires 36, 37 leading from the upper horns 32, 33 of the elevators, cross the lower wires 34, 35 in the fuselage, and are each secured to the apertured shank 83 on the lower corner of the frame 66.

The control wire 42 on the rudders crosses control wire 41 within the fuselage, and the inner ends of each are secured to the opposite apertured shanks 83 of the coupling fork on the horizontal spindles 69, 70. The aileron controls 18 connected, to the ends, of the cross bar 27, operate the ailerons in a manner heretofore described.

35. From the foregoing, it will be seen that a rocking movement to one side or the other of the steering post 71, in any position, will cause the ailerons to rock up or down on their axis. By rotating the steering post 71, the frames 66 will be rotated on its vertical axis, in any position, thereby operating the rudder 38 to one side or the other.

40. By moving the steering post 71 either forwardly or backwardly on pivots 65, the elevators 30, 31 will be moved upwardly or downwardly as desired. It will be seen that the assembled control mechanism herein disclosed will selectively or simultaneously operate the ailerons, the elevators, or the rudders, as desired.

45. It is to be understood that by describing in detail herein, any particular form, structure, or arrangement, it is not intended to limit the invention beyond the terms, of the several claims, or the requirements of the prior art.

Having thus described my invention, what I claim as new is:—

1. In a control mechanism for aeroplanes, comprising a longitudinal shaft adapted to be journaled in a fuselage of an aeroplane, a cross bar on the forward end of the shaft having control wires secured to its opposite free ends for moving the ailerons of an aeroplane, a frame rockable on the shaft at its rear end,

control wires for the elevators secured to opposite vertical points of the frame, control wires for the rudders secured to the frame at opposite horizontal points on the frame, the opposed vertical and horizontal points having a pivotal connection between the frame and the control wires, a steering post projecting from the frame and secured thereto, and stop members secured to the shaft and fuselage for limiting the movement of the frame and the cross bar respectively.

2. In a control mechanism for aeroplanes, comprising a longitudinal shaft adapted to be journaled in a fuselage of an aeroplane, a cross bar on the forward end of the shaft having control wires secured to its opposite free ends for moving the ailerons of an aeroplane, a frame rockable on the shaft, at its rear end, control wires for the elevators secured to opposite vertical points of the frame, control wires for the rudders secured to the frame at opposite horizontal points on the frame, the opposed vertical and horizontal points having a pivotal connection between the frame and the control wires, a steering post projecting from the frame and secured thereto, stop members secured to the shaft and fuselage for limiting the movement of the frame and the cross bar respectively, and said frame being four sided with the opposed corners disposed in vertical and horizontal position.

3. In a control mechanism for aeroplanes, comprising a shaft, a bearing for rotatably supporting the shaft adapted to be secured to the fuselage of an aeroplane, a cross bar secured intermediate its ends to the forward end of the shaft, a sleeved fork rigidly secured to the rear end of the shaft, a frame having a pair of spindles projecting from the opposite sides, and a pair of collars on the frame between the spindles, a stub shaft projecting through one of the collars and secured thereto, and having pins on its opposite sides, said stub shaft terminating interiorly of the frame, a steering post secured in the other collar and terminating interiorly of the frame, an elongated sleeve extending across the frame and supported on the free ends of the steering post and stub shafts, coupling forks journaled on the spindles, stub shafts, and steering posts, control means coupled to the coupling forks for the elevators and the rudder, and control means connected to the free ends of the cross bar for the ailerons.

In testimony whereof I affix my signature.
ROMEO GUILLEMETTE.
